(57) **CLAIM**

The ornamental design for a hanging sculptured self-watering flower pot, as shown and described.

DESCRIPTION

FIG. 1 is a front top perspective view of a “hanging sculptured self-watering flower pot” showing my new design;

FIG. 2 is a right side elevational view thereof, the left side elevational view being the mirror image thereof;

FIG. 3 is a top plan view thereof; and,

FIG. 4 is a bottom plan view thereof.
